UNITED STATES PATENT OFFICE.

HERBERT A. KINNEY, OF CHICAGO, ILLINOIS.

DESIGN FOR A CHAIR.

SPECIFICATION forming part of Design No. 34,756, dated July 9, 1901.

Application filed May 27, 1901. Serial No. 62,169. Term of patent 7 years.

To all whom it may concern:

Be it known that I, HERBERT A. KINNEY, a citizen of the United States, residing at Chicago, in the county of Cook and State of Illinois, have invented and produced a new and original Design for Chairs, of which the following is a specification, reference being had to the accompanying drawing, forming a part thereof.

The drawing is an elevation of a chair, showing my new design.

As shown in the drawing, the leading or material features of my design consist of an ornamental panel having formed upon its outer surface the representation of a horseshoe, and an elliptical opening formed in said panel and partially surrounded by said horseshoe.

The back for the chair, as shown, is com-

posed of side members 3, connected by a top 20 rail 4, and located between these parts and the seat 5 of the chair 1 is the ornamental panel 6, upon which the horseshoe is formed, the opening 7 being located in respect to said horseshoe in the manner before described. 25

Having described my invention, what I claim as new, and desire to secure by Letters Patent, is—

The design for a chair, as herein shown and described. 30

In testimony whereof I have signed my name to this specification in the presence of two subscribing witnesses:

HERBERT A. KINNEY.

Witnesses:

NINA E. McCOOL,
W. R. HOWLAND.
